(57) **CLAIM**

The ornamental design for a toy space drone, as shown and described.

DESCRIPTION

FIG. 1 is a front right perspective view of a toy space drone showing my new design.

FIG. 2 is a front perspective view thereof.

FIG. 3 is a rear perspective view thereof.

FIG. 4 is a left side perspective view thereof.

FIG. 5 is a right side perspective view thereof.

FIG. 6 is a top perspective view thereof; and,

FIG. 7 is a bottom perspective view thereof.

The broken lines illustrate portions of the toy space drone that form no part of the claimed design.
